UNITED STATES PATENT OFFICE.

JOSEPH B. HAMILTON, OF SAN ANTONIO, TEXAS

COLLAR-SHAPING MACHINE.

1,017,291.

Specification of Letters Patent.

Patented Feb. 13, 1912.

Application filed July 24, 1909, Serial No. 509,358. Renewed July 22, 1911. Serial No. 640,036.

To all whom it may concern:

Be it known that I, JOSEPH B. HAMILTON, a citizen of the United States, residing at San Antonio, in the county of Bexar and State of Texas, have invented a new and useful Collar-Shaping Machine, of which the following is a specification.

This invention relates to improvements in machines for shaping collars, and the particular purpose of the invention is to produce a machine of few parts which may be easily operated and by which fold-over collars may be quickly and perfectly shaped.

The preferred embodiment of my invention is illustrated in the accompanying drawings, and the invention consists in certain novel features of the same which will be hereinafter first fully described and then distinctly claimed.

20 In the drawings, Figure 1 is a side elevation of the machine showing the collar holding ring lowered from the steam shaping chest. Fig. 2 is a front elevation showing a collar holding ring moved into position under the shaping chest. Fig. 3 is a plan view of the machine, Fig. 4 is a detail horizontal section. Fig. 5 is a transverse section of a collar-holding ring. Fig. 6 is a detail sectional view.

30 The frame of the machine comprises a base plate 1 and a standard 2 rising therefrom to a proper height to permit the working parts to be readily controlled by the operator, the base plate being secured by bolts or otherwise to the floor of the laundry, as will be readily understood. Upon the front side of the standard 2 are guides or bearings 3 in which is mounted a reciprocating rod 4 having a collar 5 secured thereto by a set screw 6 between the bearings, as clearly shown, while around the rod between said collar and the lower bearing I place a buffer 7 of rubber or other elastic material which receives the impact of the collar so as to cushion the blow of the reciprocating rod upon the descent of the same. Upon the upper bearing 3 is a guide or bracket 8 in the outer end of which a pin 9 is adapted to move, the said pin depending from one of a pair of divergent arms 10 which are secured to the upper end of the rod 4. The said arms 10 serve as guides upon which slides 11 are movably mounted, the said slides carrying the collar supporting rings 12 which are swiveled upon the slides so as to be easily rotated at the will

of the operator to permit the work of inserting the collar to be most conveniently and expeditiously performed. These collar holding members consist of metal rings of proper dimensions having springs or other holding fingers 13 secured on their inner sides to engage the inner edge or fold of the collar and thereby hold the collar over the upper edge of the ring in position to be inserted into the shaping groove of the steam drum 14, as will be readily understood. The steam drum 14 is a hollow body having a V-shaped groove 15 in its underside and provided with suitable steam inlet and outlet pipes 16 and 17 so that the drum may be readily heated and maintained at the desired temperature. The drum is rigidly secured to the upper end of the standard 2 which is formed into an overhanging arm in order that the drum may be brought into the proper position to be readily engaged by the collar holding rings. Two of the collar holding rings are provided in order that while the collar on one ring is being shaped, a collar may be fitted upon and secured to the other ring.

In order to raise the collar holding ring into engagement with the steam drum and to lower it from said engagement, I employ treadles 18 and 19 which are mounted upon the base plate 1. The treadle 19 has its inner or upper end pivotally attached to a socket 20 in which a pin 22, pivotally attached to the lower end of the reciprocating rod by means of a knuckle 23, plays a spring 24 being coiled around the said pin between the socket and the knuckle so as to hold the parts in their proper operative positions and permit a slight lost motion to prevent breakage of the pivotal connections. A bracket 25 projects forward from the standard 2 between the treadles, and upon the forward end of the said bracket is pivoted a knocker 26 in the form of a short bar extending transversely in front of the treadles and adapted to be struck by the upper end of that treadle which is depressed by the operator so that the knocker will be vibrated and its opposite end caused to strike the other treadle and thereby throw the said treadle in the opposite direction.

It is thought the operation and advantages of my improved machine will be readily understood and appreciated from the foregoing description, taken in connection with the accompanying drawings. The

operator places a collar over the upper edge of one of the collar-holding rings 12 and then slides the said ring toward the inner end of the arm 10 upon which the said ring 5 is mounted. The treadle 19 is then depressed so as to swing its inner end forward and thereby cause the reciprocating rod carrying the diverging arms 10 to rise so that the collar will be forced into the recess in 10 the underside of the steam chest and will, consequently, be thoroughly smoothed and shaped. The ring 12 is left in its engagement with the steam chest while another collar is placed in position upon the other 15 ring 12, and after the collar has been thoroughly ironed, the treadle 18 is operated to lower the reciprocating rod and thereby bring the ring downward out of engagement with the steam chest. This ring is 20 then moved out from under the steam chest and the ring carrying the unfinished collar is moved into position under the steam chest so that the collar will be in position to enter the groove in the same. When the treadle 25 19 is depressed so as to raise the reciprocating rod, the inner end of the said treadle will be brought against the knocker 26 so as to vibrate the said knocker and cause the opposite end of the same to strike the end 30 of the treadle 18 and thereby raise the said treadle into position to be engaged by the operator. After the collar has been pressed, the operator depresses the treadle 18 and thereby actuates the knocker so as 35 to carry the same against the upper end of the treadle 19 and throw the said end in-

ward so that the reciprocating rod will be brought downward to lower the collar holding ring, as will be readily understood.

The device is extremely simple in its construction, can be manufactured at a slight cost, is easily operated, and efficiently accomplishes the desired results.

Having thus described my invention, what I claim is:—

1. In a collar-shaping machine, the combination of a hollow drum having a collar receiving groove in its under face, a pair of diverging arms arranged below the said drum and having their inner ends joined in the plane of the center of the drum, collar-holding rings slidably mounted on said arms, and means for raising and lowering said arms.

2. The combination of a standard, a hollow drum supported by the upper end of the standard and having a collar-receiving groove in its under side, a reciprocating rod mounted vertically on the standard in alignment with the center of the drum, a pair of horizontal guides secured to the upper end of the said rod and diverging therefrom, collar-holding rings slidably mounted on the said guides, and means for reciprocating the said rod.

In testimony that I claim the foregoing as my own, I have hereto affixed my signature in the presence of two witnesses.

JOSEPH B. HAMILTON.
